(57) **CLAIM**

The ornamental design for a display screen of mobile device with animated graphical user interface, as shown and described.

DESCRIPTION

FIG. 1 is a front view of a first image in a sequence for a display screen of mobile device with animated graphical user interface showing our new design of a first embodiment;

FIG. 2 is a front view of a second image of the first embodiment;

FIG. 3 is a front view of a third image of the first embodiment;

FIG. 4 is a front view of a fourth image of the first embodiment;

FIG. 5 is a front view of a first image in a sequence for a display screen of mobile device with animated graphical user interface showing our new design of a second embodiment;

FIG. 6 is a front view of a second image of the second embodiment;

FIG. 7 is a front view of a third image of the second embodiment;

FIG. 8 is a front view of a fourth image of the second embodiment;

FIG. 9 is a front view of a first image in a sequence for a display screen of mobile device with animated graphical user interface showing our new design of a third embodiment;

FIG. 10 is a front view of a second image of the third embodiment;

FIG. 11 is a front view of a third image of the third embodiment;

FIG. 12 is a front view of a fourth image of the third embodiment;

FIG. 13 is a front view of a first image in a sequence for a display screen of mobile device with animated graphical user interface showing our new design of a forth embodiment;

FIG. 14 is a front view of a second image of the forth embodiment;

FIG. 15 is a front view of a third image of the forth embodiment; and,

FIG. 16 is a front view of a fourth image of the forth embodiment.

In the first embodiment, the appearance of the transitional image sequentially transitions between the images shown in FIGS. 1 through 4 as the mobile device is rotated.

In the second embodiment, the appearance of the transitional image sequentially transitions between the images shown in FIGS. 5 through 8 as the mobile device is rotated.

In the third embodiment, the appearance of the transitional image sequentially transitions between the images shown in FIGS. 9 through 12 as the mobile device is rotated.

In the forth embodiment, the appearance of the transitional image sequentially transitions between the images shown in FIGS. 13 through 16 as the mobile device is rotated.

The process or period in which one image transitions to another image forms no part of the claimed design.

The broken lines shown in the drawings represent the mobile device and form no part of the claimed design.
